CLAIM

I claim, the ornamental design for a dosing cap, as shown and described.

DESCRIPTION

FIG. 1 is an elevated perspective view of a dosing cap; FIG. 2 is an inverted perspective view of the dosing cap depicted in FIG. 1;

FIG. 3 is a left side view of the dosing cap depicted in FIG. 1, where the right side view and rear view are identical to FIG. 3;

FIG. 4 is a 45 degree rotated right view of the dosing cap depicted in FIG. 1;

FIG. 5 is a top view of the dosing cap depicted in FIG. 1; and,

FIG. 6 is a bottom view of the dosing cap depicted in FIG. 1.

The broken lines in the figures depict a vial engaging the dosing cap, the vial forming no part of the claimed design.

1 Claim, 2 Drawing Sheets
